UNITED STATES PATENT OFFICE.

OLE HANSON, OF LEAD, SOUTH DAKOTA.

MINER'S TOOL.

1,184,746.

Specification of Letters Patent. Patented May 30, 1916.

Application filed March 17, 1914. Serial No. 825,368.

To all whom it may concern:

Be it known that I, OLE HANSON, citizen of the United States, residing at Lead, in the county of Lawrence and State of South Dakota, have invented certain new and useful Improvements in Miners' Tools, of which the following is a specification.

The present invention relates to new and useful improvements in miners' tools, and has particular reference to improvements in combination pocket knives.

The principal object of my invention is to provide a pocket knife or jack knife which is for the most part similarly constructed to the ordinary pocket or jack knife, and is equipped with a punch and a crimper which may be employed in punching the cap receiving opening in a stick of dynamite and then used in crimping the blasting cap on the fuse.

A further object is to provide a punch which is terminally pivoted between extensions formed on the face plates of the knife handle, and is normally adapted to lie in an out of the way position against the back edge of the knife.

A still further object is the provision of a crimping knife which consists essentially in a pair of co-acting crimping jaws, one of the jaws consisting of the knife spring and the other of the jaws being constituted by the punch.

The above and additional objects are accomplished by such means as are illustrated in the accompanying drawings, described in the following specification, and then more particularly pointed out in the claims which are appended hereto and form a part of this application.

With reference to the drawings, wherein there has been illustrated the preferred embodiment of this invention as it is reduced to practice, and throughout the several views of which similar reference numerals designate corresponding parts, Figure 1 is a perspective view of the tool or knife with the blades and punch in normal closed position; Fig. 2 is a side elevation illustrating the manner in which the punch and back spring of the knife co-operate to crimp a blasting cap on a fuse; Fig. 3 is a top plan view showing a blasting cap interposed between the back spring of the knife and the punch; Fig. 4 is a detail perspective view, illustrating particularly a blasting cap after it has been crimped on a fuse by means of my

tool; and Fig. 5 is a longitudinal sectional view more particularly showing the mounting of the crimping jaw.

In the drawings, the numerals 10 and 11 designate respectively the knife, which forms the body of the tool, and the punch member, which, as previously set forth, serves also as one of the crimping jaws. The knife 10 is similar in construction to the well known jack knife, with the exception that the face plates 12 and 13 of the knife handle are provided with terminal apertured ears 14 and 15, between which is pivotally mounted the terminal of the punch. In securing the terminal of the punch 11 between the ears 14 and 15 an ordinary pin 16 is employed, as clearly shown in Figs. 1 and 2, while the back spring of the knife is cut away to receive the said terminal and engages therewith.

A rounded head 17 is formed on the pivoted end of the punch 11, and it is through this member that the pivot pin 16 passes. A transversely extending shoulder 18 is formed in the normally outer edge of the punch adjacent the head member 17. It is now to be observed that the head member 17 is offset with respect to the longitudinal center line of the punch. The purpose in so disposing the head member is to guard against the accidental displacement or swinging of the punch when this member has been swung into operative extended position, as indicated in dotted lines in Fig. 2. When the punch is thus disposed, it will be seen that the shoulder 18 engages against the shoulder 19 formed at the adjacent terminal of the back spring. Now, since the longitudinal center line of the punch lies between the pivot pin 16 and the shoulder 18 when the punch is projected, as in Fig. 2, it is obvious that a thrust exerted on the punch in the act of inserting this member in a stick of dynamite will have little or no tendency to swing the punch into inoperative position.

In the back of the knife spring 20 is formed a substantially semi-circular transversely extending recess 21. This recess 21 is flanked on each side by semi-circular recesses 22 formed in the face plates 14 and 15 of the knife handle. These lateral recesses 22 are somewhat deeper than the recess 21, so that the metal of the blasting cap, which is indicated at 23 in Fig. 3, may be compressed or crimped by the face of the recess 21, acting in connection with

a similar and registering semi-circular recess 24 formed in the adjacent edge of the punch 11. The inner edge of the punch 11 is cut away as best shown in Figs. 1 and 5 2 of the drawings to provide laterally extending recesses arranged one upon each side of the notch 24 and communicating therewith while the outer edge of the back spring 20 is similarly cut away to provide 10 laterally extending recesses arranged one upon each side of the notch 21 and communicating therewith, these lateral recesses of the punch being adapted to mate with the lateral recesses of the back spring as 15 illustrated. Consequently, when a fuse cap is operated on, as disclosed in Fig. 2, portions of the cap will be compressed into the said laterally extending mating recesses, it, of course, being impossible to crimp that 20 portion of the cap which is positioned within the recesses 21 and 24 without forming laterally extending flanges or crimps in the metal. The recesses 21 and 24 are, therefore, provided with relatively sharp edges 25 so that, when the punch 11 is pressed toward the handle 10, the opposed edges of the two recesses will co-act to pinch the metal and produce the longitudinally extending laterally projecting crimps, indicated at 25 in Fig. 2.

It will be seen upon reference to Figs. 2 and 4 particularly that after the fuse has been inserted in the blast cap and the cap has been operated on by my tool, the metal 35 of the cap is so crimped that a central tube or portion 26 is formed intermediate the length of the cap, and that this member 26 is of considerable less diameter than the major portion of the cap. The fuse is thus 40 firmly and securely clamped in the blasting cap. After the cap has been crimped on the fuse, the punch may be swung into a projecting position with respect to the handle, as indicated in Fig. 2, and employed 45 in punching a cap receiving hole in a stick of dynamite, as has been hereinbefore explained.

In reduction to practice, it has been found that the form of this invention illustrated in the drawings, and referred to 50 in the above description as the preferred embodiment, is the most efficient and practical; yet realizing that the conditions concurrent with the adoption of this device 55 will necessarily vary, it is desirable to emphasize the fact that various minor changes in details of construction, proportion and arrangement of parts may be resorted to,

when required, without sacrificing any or the advantages of this invention, as defined 60 in the appended claims.

What is claimed is:—

1. A tool of the class described including spaced face plates, a spring interposed between the face plates, there being transversely alined notches formed in the spring and in the adjacent edges of the face plates, the notches in the face plates being of a depth greater than that of the notch of the spring, the outer edge of the spring being 70 provided with laterally extending recesses communicating with the notch formed therein, and a pivoted crimping jaw terminally connected to the face plates, said crimping jaw having a notch formed in 75 one edge adapted to mate with the notches of the spring and face plates and having its inner edge provided with laterally extending recesses communicating with the notch formed therein and adapted to mate 80 with the recesses of the spring.

2. A tool of the class described including spaced face plates, a spring interposed between said plates, there being transversely alined notches formed in the spring and in 85 the adjacent edges of the face plates, the outer edge of the spring being provided with laterally extending recesses communicating with the notch formed therein, and a crimping jaw swingingly connected to the 90 face plates, said crimping jaw having a notch formed in one edge adapted to mate with the notches of the spring and face plates and having its inner edge provided with laterally extending recesses communicating with the notch formed therein and adapted to mate with the lateral recesses 95 of the spring.

3. A tool of the class described including a body portion having face plates offset 100 adjacent one extremity of the body portion, a spring carried by the body portion and cut away adjacent the offset extremities of said face plates, and a crimping jaw pivotally connected to the offset portions of 105 the face plates and engaged by the cut away portion of said spring, the jaw being movable to coöperate with the face plates and with the spring.

In testimony whereof I affix my signature 110 in presence of two witnesses.

OLE HANSON. [L. S.]

Witnesses:

J. WM. STONER,
MARY E. HASTIE.
